UNITED STATES PATENT OFFICE.

CHRISTOPHER H. SEVERS, OF CHICAGO, ILLINOIS.

SAFETY-LOCK FOR SWITCH-STANDS.

1,399,808.

Specification of Letters Patent. Patented Dec. 13, 1921.

Application filed September 13, 1920. Serial No. 410,053.

To all whom it may concern:

Be it known that I, CHRISTOPHER H. SEVERS, a citizen of the United States, and a resident of Chicago, county of Cook, and 5 State of Illinois, have invented certain new and useful Improvements in Safety-Locks for Switch-Stands, of which the following is a specification.

The invention relates to switch stands and 10 seeks to provide an improved safety lock of simple, effective construction therefor. The invention consists in the improvements hereinafter set forth and illustrated in the preferred form in the accompanying drawings 15 and more particularly pointed out in the appended claims.

In the drawings Figure 1 is a view in elevation of a switch stand with the present improvement applied thereto;

20 Fig. 2 is a vertical section of the improved safety lock taken on the line 2—2 of Fig. 3;

Fig. 3 is a vertical section on the line 3—3 of Fig. 2;

25 Fig. 4 is a partial end view of the safety lock support; and

Fig. 5 illustrates a form of key which may be employed to release the lock.

The improved safety lock is more particularly adapted for switch stands such as 30 illustrated in Fig. 1 and comprising a body portion 1 adapted to be mounted between two ties 2 and having a horizontal operating shaft 3 provided with a throw lever 4 which is arranged to be moved through substantially 35 180° to open and close the switch connected to the stand, the lever being provided, as shown, with an outer weighted end 5. At one side of the stand is mounted an upright support 6 which carries a suitable latch 7 for 40 holding the throw lever in the position shown in dotted lines in Fig. 1 with the switch open. This latch may be of any suitable construction and, as usual, is adapted to be manually released.

45 At the other side of the stand is provided the safety lock attachment and which is carried by an upright cast metal support 8 having a base flange 9 by which it is spiked to the adjacent tie. At its inner end the support 50 is provided with an upwardly opening recess or seat 10 which is arranged to receive the throw lever 4 when the latter is in the position shown in full lines in Fig. 1 with the switch closed. Preferably, like the support 55 6, the support 8 is provided with a manually releasable pivoted latch 11 for holding

the lever in the seat 10. In addition to the latch, safety locking means are provided for holding the lever in this position and thereby preventing the unauthorized opening of 60 the switch.

In the preferred construction shown the upper portion of the support is provided with an opening 12 extending therethrough and communicating with the upper portion 65 of the seat or recess 10, the wall or portion of the support on the opposite side of the recess being provided with an opening 13 in line with the opening 12. The openings 12 and 13 are adapted to receive a removable 70 locking bolt 14 which, in the locking position shown in Fig. 2, prevents the movement of the throw lever 4. To prevent rotary movement of the bolt the openings 12 and 13 are 75 square in cross section and the bolt is provided at its outer end with an upturned perforated portion or handle 15 and the latter, in the form shown, is provided with a laterally projecting target 16. In a railway system or yard in which the present safety 80 devices are employed the locking bolts are carried by employees who may be required to work upon a track and wish to prevent the opening of the switch controlling the track while they are at work. Under such circumstances the operating lever 4 of the controlling switch will be thrown to the position shown in full lines in Fig. 1 to close the switch and one of the locking bolts inserted 85 as shown in Fig. 2.

To prevent the insertion of one of the locking bolts by a careless workman without closing the switch, a stop 17 is arranged to slide vertically within a slot or recess 18 formed in the support 8 adjacent the seat 90 10. The lower end of the stop is provided with a laterally extending portion 19 arranged within a recess 20 in the support and is fixed to a vertically movable member 21 the upper end of which extends into the 100 lower portion of the recess or seat 10. A spring 22 is coiled about the member 21 and extends between the portion 19 and a plate 23 seated in the lower portion of the recess 20. When the locking bolt 14 is removed 105 and the throw lever of the switch is out of the seat 10 the spring 22 holds the stop 17 elevated in the path of movement of the bolt so that the latter cannot be thrust inwardly to locking position, but when the lever 4 is 110 thrown to close the switch it will engage the member 21 and shift the stop 17 against

the tension of the spring 22 to the position shown in full lines in Fig. 2 so that the locking bolt can then be inserted.

A latch is provided for holding the bolt 14 in locking position. In the form shown this latch is carried by a block 24 which is adapted to be inserted in the corresponding recess in the outer portion of the support 8. A latch member 25 is arranged to slide vertically within a recess in the block 24 and is provided with a reduced upper end portion and a reduced cylindrical lower portion or stem 26. A spring 27 coiled about the stem 26 extends between the body of the latch and a plate 28 in the lower portion of the recess in the block. The spring 27 normally holds the latch in uppermost position with its upper end 29 extending into the opening 12 and in the path of movement of the locking bolt 14. The upper end 29 of the latch is provided with a square inner face and a beveled outer face and is arranged to engage a correspondingly shaped recess in the bolt 14 when the latter is shifted to its innermost locking position. The bolt is also provided with a beveled or cam shaped end 30 which as it is inserted is arranged to engage and depress the latch against the tension of the spring 27 but when the bolt is in locking position the spring will engage the latch with the notch of the bolt and secure it in locking position.

To effect the release of the latch the end portion of the support 8 adjacent the block 24 is provided with a keyhole 31 adapted to receive a key 32. The keyhole and key may be variously shaped to prevent tampering with the safety lock by unauthorized persons. In the form shown the inner end of the key is arranged to extend within recesses 33 and 34 formed respectively in the block 24 and latch 25 with the inner end of the key stem engaging the hole 35 of the block and the ward of the key engaging an opening 36 in the latch so that by turning the key the latch can be depressed to release the bolt 14.

To notify the yard master or other suitable official that a switch has been locked in closed position, the support 8 is preferably provided with a recess 37 within which are arranged a pair of contacts 38 arranged to control a signal circuit. These contacts are normally open but are adapted to be engaged by a switch actuator 39 having a head 40 arranged within the recess 41 formed in the support above the recess 37. A spring 42 is coiled about the actuator and extends between the head 40 and a plate 43 arranged in the lower portion of the recess 41. Normally the switch actuator 39 is held elevated by the spring 42 and the signal contacts 38 are open but, when the locking bolt 14 is inserted, its beveled end 30 with engage a beveled portion 44 of the

head 40 and depress the actuator as shown in Fig. 2 to thereby engage the contacts.

The recesses carrying the latch block 24, stop 17, signal contacts and actuator open through one of the side faces of the support 8 and are closed by a cover plate 45 secured in position by screw bolts 46.

To prevent access of moisture and dirt through the openings 12 and the keyhole 31, the outer ends of these openings are preferably closed by a pair of vertical movable slides 47 carried by a plate 48 that is fixed to the upper portion of the outer face of the support 8. The plate is provided with guiding recesses 49 for the slides and with openings registering with the opening 12 and keyhole 31 and which openings are normally closed by the slides. The latter are provided with projections 50 so that they can be lifted to permit the insertion of the bolt 14 and key 32.

Obviously changes may be made in the details set forth without departure from the essentials of the invention as defined by the claims.

I claim as my invention:

1. In a switch stand, the combination with an operating shaft and throw lever therefor, of a support having a seat for receiving said lever when the latter is at one end of its throw, a bolt insertible into said support for locking said lever in said seat, and means for preventing the shift of said bolt to locking position when said lever is out of said seat.

2. In a switch stand, the combination with an operating shaft and throw lever therefor, of a support having a seat for receiving said lever when the latter is at one end of its throw, a bolt removably engaging said support and arranged to lock said lever in said seat, and a stop adapted to be tripped by said lever for preventing the movement of said bolt to locking position when said lever is out of said seat.

3. In a switch stand, the combination with an operating shaft and throw lever therefor, of a support having a seat for receiving said lever when the latter is at one end of its throw, a bolt insertible into said support for locking said lever in said seat, a stop for preventing the shift of the bolt to locking position, said lever being arranged to trip said stop when in position in said seat, and a key controlled latch for holding said bolt in locking position.

4. In a switch stand, the combination with an operating shaft and throw lever therefor, of a support having a seat for receiving said lever when the latter is at one end of its throw, a bolt insertible into said support to lock said lever in said seat, and a key-controlled, spring-actuated latch carried by said support for holding said bolt in locking position.

5. In a switch stand, the combination with

an operating shaft and throw lever therefor, of a support having a seat for receiving said lever when the latter is at one end of its throw, a bolt removably engaging said support for locking said lever in said seat, a spring-held stop for preventing the movement of said bolt to locking position, said lever being arranged to trip said stop when in position in said seat, and a key-controlled latch carried by said support for securing said bolt in locking position.

6. In a switch stand, the combination with an operating shaft and throw lever therefor, of a support having a seat for receiving said lever when the latter is at one end of its throw, a bolt insertible into said support for locking said lever in said seat, and a key-controlled latch for holding said bolt in locking position, said support having a recess 20 in which said latch is mounted.

7. In a switch stand, the combination with an operating shaft and throw lever therefor, of a support having a seat for re-

ceiving said lever when the latter is at one end of its throw, a bolt adapted to be inserted through said support for locking said lever in said seat, a stop preventing the shift of said bolt to locking position but arranged to be tripped by said lever when the latter is moved into said seat, and a key-controlled latch for holding said bolt in locking position, said support having covered recesses in which said stop and latch are mounted.

8. In a switch stand, the combination with an operating shaft and throw lever therefor, of a support having a seat for receiving said lever when the latter is at one end of its throw, a bolt coöperating with said support for locking said lever in said seat, a key-controlled latch for securing said bolt in locking position, signaling contacts and an actuator therefor controlled by said bolt, said contacts and actuator being arranged with recesses in said support.

CHRISTOPHER H. SEVERS.
